DESIGN FOR AN ARTICLE DISPLAY CASE

Thomas J. Pilliod, Swanton, Ohio, assignor to
The Pilliod Cabinet Company, Swanton, Ohio,
a corporation of Ohio

Application March 25, 1937, Serial No. 68,395

Term of patent 7 years

To all whom it may concern:

Be it known that I, Thomas J. Pilliod, a citizen of the United States and resident of Swanton, county of Fulton, State of Ohio, have invented a new, original, and ornamental Design for an Article Display Case, of which the following is a specification, reference being had to the accompanying drawing, forming a part thereof.

Fig. 1 is a perspective view of an article display case showing my new design; Fig. 2 is an end view thereof, and Fig. 3 is a section on the line 3—3 in Fig. 1.

The cover member A shown in full lines is of transparent material having the beads B formed thereon.

I claim:

The ornamental design for an article display case, substantially as shown and described.

THOMAS J. PILLIOD.
